UNITED STATES PATENT OFFICE.

JOSEPH A. HUMM, OF ELYRIA, OHIO.

SWEEPER.

1,044,052.

Specification of Letters Patent. Patented Nov. 12, 1912.

Application filed June 24, 1911. Serial No. 635,239.

To all whom it may concern:

Be it known that I, JOSEPH A. HUMM, a citizen of the United States, residing at Elyria, in the county of Lorain and State 5 of Ohio, have invented a certain new and useful Improvement in Sweepers, of which the following is a full, clear, and exact description.

This invention relates to street cleaning 10 apparatus and provides a device which will remove dirt and refuse from the surface upon which it operates, and elevate and convey the same to a receptacle, which may be a wagon, to which the cleaning device may 15 be attached.

Generally speaking, the invention comprises the elements and combinations thereof set forth in the accompanying claims.

Reference should be had to the accompanying drawings forming a part of this 20 specification, in which—

Figure 1 is a side elevation with the cover partially removed; Fig. 2 is a top plan view with the cover removed; Fig. 3 is a central 25 longitudinally vertical section of a portion of the device; Fig. 4 is a plan partially in section showing a detail of construction and is taken upon the line 4—4 of Fig. 1.

1 and 2 represent the side members of a 30 frame which at its forward end is joined by means of a cross member 3. At their rear ends, the members 1 and 2 are secured upon an axle 4, upon which are mounted wheels 5 and 6. At the forward end, the side members 1 and 2 are mounted upon wheels 7 and 8, by means of an ordinary construction, such as is present in all wagons, permitting 35 the front wheels to turn upon a central axis.

Depending from the members 1 and 2 are 40 vertical bars, one of which is represented at 9, in Fig. 1, and the other represented at 10 in Fig. 3. These bars at their lower ends are joined with the members 1 and 2 by means of bent braces 11 and 12. These 45 braces 11 and 12 extend slightly beyond the bars 9 and 10, and upon their free ends there are pivoted members 13 and 14, which I term supports, as will be clearly seen in Figs. 1 and 2. These members 13 and 14 extend toward the rear of the device and upon 50 these last mentioned members are mounted the opposite ends of a brush shaft 15, this shaft being mounted in suitable journal boxes, one of which is indicated at 17, the 55 manner of mounting being of no particular

importance. Upon the shaft 15 is a brush generally indicated at 18 which may be of any desired construction, being stiff and strong enough to elevate such material as it may be required to act upon. 60

Partially surrounding the brush is a hood 19, the same extending above the brush a sufficient distance to direct the material raised by the brush toward a conveyer which will later be described. Upon the outside of 65 the hood is a receptacle or pocket 20 which is adapted to contain suitable material to place sufficient weight upon the hood to hold it down. This hood is provided with ends indicated at 21, and these ends are pivoted 70 upon the brush shaft 15, the construction being such that the hood 19 is freely movable upon this shaft.

Cooperating with the hood 19 is a scraper 22, the same being provided with substantially vertical ends represented at 23, and these ends are pivotally mounted upon the brush shaft 15 in such a manner that they are freely movable thereon. The scraper is provided with a sharpened edge in order 75 80 that it may dislodge the material upon which the brush is intended to act. The scraper at its rear edge bears against the lower portion of the hood 19, by which it is firmly held in its position. 85

Upon each of the members 13 and 14 is pivoted a lever 24 and 25, which at its lower end is bent at an angle to the main portion, and at the lower part of the bent portion are mounted wheels 26 and 27. At their 90 upper ends the levers 24 and 25 are pivotally secured to links 28 and 29, which extend toward the rear end of the device and are in turn secured to levers 30 and 31, which are respectively pivoted upon the side members 95 1 and 2. These levers 30 and 31 are provided with handles, and with locking pawls, which are of ordinary construction, so that the levers 30 and 31 may be held or located in any adjusted position. By the manipulation of these levers, the position of the levers 24 and 25 may be varied, and thereby the wheels 26 and 27 may be moved with respect to the pivoted side members 13 and 14 and by so much the position of the brush 100 105 with respect to the surface upon which it is acting may be raised. This movement may be such as to raise or lower the brush, and further, inasmuch as the levers 30 and 31 may be independently moved, it is possible 110

to adjust the opposite ends of the brush independently of each other. Such an adjustment is of great importance in cleaning streets, for it permits the ends of the brush 5 to be lowered, if the street is not level, and most streets are not. It should further be noted that the auxiliary frame which carries the brush has a certain latitude of movement, for it is not rigidly held and therefore it 10 may accommodate itself to the lesser irregularities of the surface upon which it operates.

A shaft 32 is mounted near the opposite ends thereof upon the horizontal portion of the braces 11 and 12. Near opposite ends of this shaft there are mounted sprocket wheels 33 and 34 which upon their outer faces are provided with clutch teeth. Upon the same shaft 32 at the opposite ends thereof, but unsecured to the shaft, are sprocket wheels 35 and 36 which are also provided with clutch teeth upon their inner faces that coöperate with the clutch teeth upon the sprocket wheels 33 and 34. These sprocket 25 wheels 35 and 36 are held in engagement with the sprocket wheels 33 and 34 by means of springs, one of said springs 37 being shown in Fig. 4. The spring 37 is seated within a cup shaped member 38 which is held in place by a nut 39 that may be locked in position.

Between the sprocket wheels 33 and 35 is another spring 40 which surrounds the shaft 32. This spring tends to push the two sprocket wheels apart, but is weaker than the spring 37, and therefore normally is inoperative. However, if the nut 39 be loosened so as to relieve the tension of the spring 37, the spring 40 will immediately 40 act and push the sprockets 33 and 35 apart, thereby destroying their driving relationship. This construction just described is duplicated with respect to sprocket wheels 34 and 36. From this it will be apparent 45 that when desired, the brush, as will later appear, may be operatively disconnected from the wheels of the device which furnish the motive power. This construction permits the apparatus to be drawn from place 50 to place without necessarily operating the cleaner brush and elevator. The clutch mechanism between the sprockets 33 and 35 and the sprockets upon the opposite side of the shaft permits the apparatus to turn 55 corners without strain upon the mechanism.

Each of the wheels 5 and 6 carry an annular sprocket wheel 41 and 42. The sprocket wheel 41 is operatively connected with the sprocket wheel 35 by means of a sprocket 60 chain 43, while the sprocket wheels 42 and 36 are similarly connected by a chain 44.

Upon the opposite ends of the brush shaft 15 are sprocket wheels 46 and 47, which by means of sprocket chains 48 and 49, are operatively connected with the sprockets 33

and 34. By means of these connections, the motion of the wheels 5 and 6 produces rotation of the brush 18.

At the forward end of the device is an elevator which in this instance is of the endless bucket variety, which is adapted to convey material supplied thereto by the brush, into any suitable receptacle. This elevator is formed with side pieces 50 and 51 which at their inner ends are pivoted upon the shaft 32. At their opposite ends, the members 50 and 51 are joined by means of a rod 52. Extending between the side pieces 50 and 51 is a partition 53 which prevents any material spilling from the buckets from falling 70 through. This partition or floor 53 is in close proximity to the lower portions of the buckets and any material which collects upon this floor is carried along by engagement with the buckets and deposited in the 75 proper receptacle.

Near the opposite ends of the rod 50 are sprocket wheels 54 and 55 which are loosely mounted upon the rod 52. Upon the shaft 32 are secured the sprocket wheels 56 and 57 which sprocket wheels are adapted to turn with the shaft 32. Passing over the sprocket wheels 54 and 56, as well as the sprocket wheels 55 and 57, are sprocket chains 58 and 59, and extending between the 80 sprocket chains 58 and 59 are a series of buckets indicated at 60, which operate in a manner easily to be understood. At its lower or inner end, this bucket conveyer is placed sufficiently close to the brush so that the material raised by the brush will be deflected by the hood 19 upon the conveyer, this material finding lodgment in the buckets, and as before stated, such material as falls between the buckets will be carried 85 along by engagement with the buckets and deposited in the receptacle.

Any suitable receptacle may be provided to receive the material from the conveyer, but it is the intention to use this device in 90 connection with a wagon, and to so place the conveyer that the material carried thereby will be deposited in the wagon, as is indicated in Fig. 1. With this in view, the axle 95 for the front wheels of the cleaning apparatus may be provided with a tongue 61 which may be fastened in any desired manner, as indicated at 62 in Fig. 1.

The conveying mechanism as a whole may be moved with respect to the frame of the 100 cleaning device about the shaft 32 as a pivot, and the elevating device will be held in position by means of pins, one of which is shown at 63 which may engage in various 105 openings formed in the sides 50 and 51 and the members 1 and 2.

At the rear end of the apparatus, a platform 66 is supported from the side members 1 and 2, by means of vertical hangers 67 and 68, as represented in Figs. 1 and 3. Upon 110

this platform the attendant of the device may stand and manipulate the levers 30 and 31 as necessary.

It is often desirable to lift and retain the brush out of contact with the street, especially when the device is being taken from place to place. Therefore, I provide means upon the vertical pieces 67 and 68 by which the members 13 and 14 of the auxiliary frame 5 may be secured in raised position. The simplest form of such means may be pins, one of which is shown at 69 in engagement with an opening in member 68. The support 13 may be raised to rest upon the pin 69; the same construction will be provided upon the opposite side of the device, and in this manner the supports for the brush and therefore the brush may be raised and held. It is possible to raise the brush 15 off of the surface to be cleaned by the levers 30 and 31, but for some purposes I prefer the construction just set forth.

A cover 70 is provided which is supported upon the side members 1 and 2 of the frame 25 and covers the parts of the device which might throw dust. The conveyer extends through an opening in this cover and, if necessary, an auxiliary hood may be provided which will also serve to direct the material 30 being discharged into the receptacle.

Having thus described my invention, what I claim is:

1. In a device of the character described, the combination with a frame, wheels upon 35 which said frame is mounted, a platform supported by the frame upon which the operator of the device may stand, operating hand levers pivoted upon the frame adjacent to said platform, supports pivotally carried by said frame, a rotatable brush journaled upon said supports, wheels beneath said supports, means adjustably mounting the supports upon the wheels, connections between said adjustable means and said hand 45 levers whereby the wheels may be adjusted relative to the supports from the operator's platform, and operative connections between one of the wheels upon the frame and said brush to operate the same.

50 2. In a device of the character described, the combination with a frame, wheels upon which said frame is mounted, a platform supported by the frame upon which the operator of the device may stand, operating hand levers pivoted upon the frame adjacent to said platform, supports pivotally carried by the said frame, pivoted levers carried by the supports, which levers are operatively connected with the operating hand 55 levers, wheels adapted to travel upon the

same surface as the brush, said wheels being carried by the pivoted levers, a rotatable brush mounted upon said supports, a conveyer mounted in the frame and adapted to receive material swept by the brush, an operative connection between one of the wheels upon the frame, the brush and the conveyer, whereby the brush and conveyer are operated.

3. In a device of the character described, the combination with a frame and wheels upon which said frame is mounted, hangers depending from the first mentioned frame, supports hingedly secured at one of their ends to the hangers, a brush, the opposite 75 ends of which are mounted upon the supports, levers pivoted upon the supports, wheels carried at the lower ends of the said levers and adapted to contact the surface upon which the brush is operating, means 80 for independently moving the said levers and holding them in adjusted position, and means for rotating said brush.

4. In a device of the character described, the combination with a frame and wheels 85 upon which said frame is mounted, of supports pivotally carried by the first mentioned frame, the supports being independently movable, a brush having the opposite ends thereof mounted upon the supports, levers 90 pivoted upon the side members of the auxiliary frame, wheels mounted at the lower end of said levers, a platform mounted upon the first mentioned frame, hand levers mounted upon the first mentioned frame adjacent 95 said platform, operative connections between the said hand levers and the levers pivoted upon the sides of the auxiliary frame, whereby the said levers may be independently adjusted, and means for rotating the said brush.

5. In a device of the character described, the combination with a frame and wheels upon which the said frame is mounted, of supports pivotally carried by the first mentioned frame, a rotatable brush carried by the supports, an elevator supported by the frame, one end of the same being in proximity to the brush, a shield partially surrounding the said brush and directing the material 105 raised by the brush upon the said elevator, and a scraper supported by the auxiliary frame and adapted to engage the surface upon which the brush is operating.

In testimony whereof, I hereunto affix my 110 signature in the presence of two witnesses.

JOSEPH A. HUMM.
